UNITED STATES PATENT OFFICE.

JOSEPH MERRITT AND CHARLES H. STORRS, OF HARTFORD, CONNECTICUT, ASSIGNEES,
BY DIRECT AND MESNE ASSIGNMENTS, TO THE HARTFORD LOCK RING COMPANY,
OF HARTFORD, CONNECTICUT, A CORPORATION OF CONNECTICUT.

MACHINE FOR FEEDING RINGS.

1,134,887.

Specification of Letters Patent.

Patented Apr. 6, 1915.

Application filed April 4, 1912, Serial No. 688,499. Renewed May 7, 1914. Serial No. 837,082.

To all whom it may concern:

Be it known that we, JOSEPH MERRITT and CHARLES H. STORRS, citizens of the United States, residing at Hartford, in the county 5 of Hartford and State of Connecticut, have invented a new and useful Improvement in Machines for Feeding Rings, of which the following is a specification.

This invention relates to a machine which 10 is particularly designed for feeding light, small split rings in such manner that they are in position for subsequent treatment, although the invention may be adapted for feeding other articles.

15 The object of the invention is to provide a comparatively simple machine which will run with a minimum expenditure of power and rapidly collect rings from a promiscuous mass thrown into a hopper and deliver them 20 in a uniform manner. This object may be attained by providing a hopper having inclined walls with an opening at the bottom, below which opening is the tip of a collecting rod. The rings are put into the hopper, 25 and sliding down the side walls drop out of the opening. Some drop onto and are caught by the collecting rod, down which they pass. Others escape and drop into a rotary elevator which carries them up and 30 pours them back into the hopper. If the rings are split, and the machine shown is designed to feed split rings, as the rings pass down the collector rod they are manipulated so as to be turned and fed with all the open- 35 ings in line with each other. This is accomplished by providing the collecting rod with a feather. If the rings pass down in such position that the feather enters between the opened ends, the rings continue to drop. 40 If the rings do not reach the feather in the proper position they are turned around by suitably rotated wipers until the openings between the ends are in line with the feather so that the rings will drop down. This loc- 45 ates the rings on the rod one above the other with the openings in line in such position that they may be uniformly fed to other mechanisms for subsequent treatment.

Figure 1 of the accompanying drawings 50 shows a front elevation of a machine which embodies the invention, with a portion of the casing of the rotary elevator broken away in order to show the ring carrying buckets. Fig. 2 shows a side elevation of the

machine with the hopper and rotary ele- 55 vator cut in central vertical section. Fig. 3 shows a plan of the operating mechanism, the hopper and rotary elevator being omitted. Fig. 4 shows on larger scale a plan of a wiper in the act of engaging a ring on the 60 collector rod so that the ring will be turned in order that the guiding feather may enter the opening between the separated ends of the ring. Fig. 5 shows a side elevation of the parts shown in Fig. 4. Fig. 6 shows 65 a plan of the parts shown in Fig. 4 after the wiper has turned the ring so that the opening between its ends coincides with the plane of the feather. Fig. 7 is a side view of the parts in the position shown in Fig. 6. Fig. 70 8 is a sectional view of the wiper rotating mechanism, on the plane indicated by the dotted line 8—8 on Fig. 3.

The mechanism illustrated as embodying 75 this invention is mounted on a table 1 which is clamped upon the end of a supporting post 2. The hopper 3 is mounted on four posts 4 which are supported by arms 5 projecting from the upper ends of the standards 6. The hopper has inclined bottom walls, 80 and at the lower end is an opening 7. The rings which are placed in this hopper in a promiscuous mass work by gravity down the inclined walls and drop through the opening at the bottom, the size of which may be 85 regulated by adjusting the movable gate-plate 8.

Surrounding the hopper is a cylindrical elevator 9. This elevator has buckets 10 in the interior, which, when the elevator is ro- 90 ated, carry the rings up and drop them into the hopper. On the periphery of the elevator are two annular flanges 11 and an annular rack 12. On the shafts 13 that are mounted in bearings in the upper ends of 95 the brackets 6 are hubs 14. When the elevator is in place, the flanges 11 rest loosely on the hubs 14 on the shafts 13. Flanges 15 on the edges of one set of the hubs 14 prevent sidewise displacement of the elevator. 100 When the elevator is thus located, its peripheral rack 12 meshes with a pinion 16 on one of the shafts 13. The inwardly extending flanges 17 close the sides of the elevator buckets. Doors 18 are hinged to the bottom 105 of the hopper for closing part of the opening in the sides of the elevator. On one side a button 19 is arranged on the under-

side of the elevator for the purpose of temporarily holding the door open when it is desired to inspect the interior. Plates 20 attached to the brackets 21 on the posts 4 are employed to close other portions of the opening in the sides of the elevator so as to prevent the rings from spilling out.

The collector rod 22 is located so that its tip is just below the discharge opening 10 through the bottom of the hopper in position to catch rings which drop through the opening. Such rings as the collector rod catches slide downward. The rings which are not caught drop into the elevator and are 15 carried up and returned to the hopper. The collector rod has a feather 23 which is clamped to the bracket 24 by the plate 25. At the upper end of the feather is a finger 26, and held between the bracket and the 20 clamp plate is a small guide-plate 27. If the rings follow down the collector rod with the openings in line with the feather, as shown in Fig. 6, they will continue their movement down the rod. If the openings 25 between the ends of the rings are not in line with the feather, as shown in Fig. 4, they are caught with the finger 26 projecting through them, as shown in Fig. 5. They occupy this position until they are turned around the 30 rod by the wipers or brushes into such position that the openings do coincide with the feather.

The brushes shown consist of wipers 28 clamped in a rotatable head 29 mounted on 35 a vertical arbor 30. This arbor is fixed on the end of a swinging arm 31 which is pivoted on a post 32 that is fixed to the frame. (Fig. 8.) A spring 33 (Figs. 1, 3) tends to 40 draw the arm bearing the wiper head toward the collector rod. This movement is limited by the stop screw 34 (Figs. 1, 3). In case the rings jam or get caught on the collector rod, the spring yields and allows the head to move away so that the rings are not 45 crushed, or any of the parts injured. On the lower end of the hub of the wiper head 29 is a pinion 35, engaging with which is a pinion 36 that is pivoted on a stud 37 also mounted on the arm. Engaging with the intermediate pinion 36 is a gear 38 on the hub of 50 the beveled gear 39 which is mounted on the post 32 which forms the axis of the swinging arm that carries the head. (Fig. 8.)

Meshing with the beveled gear 39 is a beveled gear 40 on a shaft 41 that is supported by bearings at the top of the brackets 42. (Figs. 2, 3.) On the end of the shaft 41, opposite the beveled gear 40 is a spur gear 43, meshing with which is a spur gear 44 on 55 one of the elevator supporting and rotating shafts 13. Connected with the gear 44 is a beveled gear 45, meshing with which is a beveled pinion 46 that is connected with the driving pulley 47. (Figs. 2, 3.)

65 The rings are thrown promiscuously into

the hopper and flow down the inclined walls to the opening at the bottom. Some of the rings in dropping through the opening are in such position that they are caught by the collecting rod, others drop into the hopper. When the mechanism is in operation, the hopper is rotated and the buckets carry the rings which drop into them up and pour them back into the hopper. This action takes place in such a way that the rings are 70 caught by the collector rod very rapidly. Such rings as pass down the collector rod with the openings between the ends in the proper position continue their downward movement past the feather and are guided by the feather in proper position for future manipulation. Such rings as pass down the 75 collector rod with the openings between their ends out of line with the feather are detained until the revolving wiper turns them so that the openings will come into line with the feather and they can continue down the rod. The wipers shown are arranged on an 80 incline so that they slightly lift the rings and tip the ends down in such manner that they are inclined to when turned engage 85 with the feather and pass down. The finger at the upper end of the feather, which passes into the rings, holds them in a manner which facilitates this, as does the guide-plate that is clamped to the bracket opposite the finger at the top of the feather. If 90 the rings catch and tend to jam, the wiper head swings away, thus eliminating any 95 danger of damage. When the jam is released, the wiper head is drawn back by its spring so as to continue its turning action 100 on the rings. This simple mechanism automatically handles small, light rings as well as larger rings very rapidly and delivers 105 them all in the same relation, that is, with the openings between the ends in alignment.

The invention claimed is:

1. A ring feeding machine having a hopper with a discharge opening, a collector rod with its tip below the discharge opening, a guiding feather, and mechanism for turning the rings on the rod so that the openings between their ends will coincide with said feather.

2. A ring feeding machine having a hopper with a discharge opening, a collector rod with its tip below the discharge opening, a feather projecting from the collector rod, and means for lifting and turning the 110 rings on the rod so that the openings between their ends will coincide with said feather.

3. A ring feeding machine having a hopper with a discharge opening, a collector rod with its tip below the discharge opening for catching rings that fall through said opening, a rotary elevator about the hopper for catching such rings as pass through the 115 hopper discharge and are not caught by the 120

collector rod, and mechanism for rotating the elevator and carrying the rings which it catches back to the hopper.

4. A ring feeding machine having a hopper with a discharge opening, a collector rod with its tip below the discharge opening for catching rings that fall through said opening, a feather projecting from the collector rod, a wiper for rotating the rings on the collector rod, mechanism for rotating the wiper, a rotary elevator for catching rings which pass through the opening and are not caught by the rod, and mechanism for rotating the elevator and returning the rings caught thereby.

5. A ring feeding machine having a hopper with inclined walls and a discharge opening at the bottom, a rotary elevator with buckets for carrying rings up and depositing them in the hopper, mechanism for rotating the elevator, a collector rod with its tip below the hopper discharge opening, a feather projecting from the rod, a rotatory wiper movable toward and from the collector rod for turning rings on the rod that are caught by the feather, means for drawing the wiper toward the rod, and mechanism for rotating the wiper.

6. A ring feeding machine having a hopper with a discharge opening, a collector rod with its tip below said discharge opening, a feather projecting from the rod, a rotatory wiper movable toward and from the rod, means for drawing the wiper toward the rod, and mechanism for rotating the wiper.

7. A ring feeding machine having a hopper with a discharge opening, a collector rod with its tip below said discharge opening, a feather projecting from the rod, a rotatory head, mechanism for rotating the head, and spirally arranged wipers on the head adapted to rotate and lift rings on the rod that are caught by the feather.

8. A ring feeding machine having a hopper with a discharge opening, a collector rod with its tip below the discharge opening, a swinging head, a rotatory wiper carried by the head, and mechanism for rotating the wiper.

9. A ring feeding mechanism having a collector rod, a rotatory wiper adjacent to the rod, and mechanism for rotating the wiper.

10. A ring feeding mechanism having a collector rod, a rotatory wiper adjacent to the rod, said wiper being adapted to lift and rotate rings on the rod, and mechanism for rotating the wiper.

11. A ring feeding mechanism having a collector rod, a swinging rotatory wiper adjacent to the rod, and mechanism for rotating the wiper.

12. A ring feeding mechanism having a collector rod, a head adjacent to the rod, mechanism for rotating the head, and wipers projecting spirally from said head adjacent to the collector rod.
